UNITED STATES PATENT OFFICE.

GEORGE A. LOCKE, OF GLEN COVE, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed October 7, 1924. Serial No. 742,152.

This invention relates, in general, to signaling systems and more particularly to submarine signaling systems employing means for associating the terminal apparatus with the cable.

In submarine cable systems it is sometimes desirable to locate certain of the apparatus at the shore station where the submarine cable terminates, although for commercial reasons the messages are transmitted and received at a point some distance from the shore station but more accessible to the public. To facilitate testing in such a system, it is advantageous to be able to control the necessary switching mechanisms from either the shore station or the cable office and to perform these switching operations in a certain sequence. More particularly is this true in the case of a long submarine cable which is operated to alternately send and receive messages, since during the sending operation, the dielectric of a long submarine cable absorbs an electrical charge of high value and if the sending apparatus is disconnected and the receiving apparatus immediately connected to the cable, the discharge of this absorbed charge will result in damage to the delicate receiving mechanism. To prevent such damage, it is desirable after disconnecting the sending apparatus to ground the cable for a period of time sufficient to permit the major portion of this charge to drain off before the receiving mechanism is connected to the cable. In patent to Austen M. Curtis, No. 1,586,971 issued June 1, 1926, there is disclosed a method of protecting the receiving mechanism of such a cable from injury during the switching operations.

The principal object of the present invention is to enable either of two stations located at one end of a transmitting conductor (for example a long submarine cable) to control signaling apparatus at both stations.

A further object of the invention is to perform the switching operations automatically and in such a manner that the delicate apparatus will not be damaged by excessive currents flowing during switching operations.

To accomplish these objects, and in accordance with a feature of the invention, the two stations located at one end of a submarine cable are joined by an operating loop and a control loop. Control means are provided at each of the stations for controlling the switching mechanisms operated at both stations and for associating the transmitting and receiving mechanisms located at both stations with the operating loop.

In accordance with another feature of the invention, during a certain time interval various switching operations are performed in a desired sequence and at such a speed as to preclude the possibility of damage to the receiving mechanism when it is connected to the cable.

These and other features of the invention may be more clearly understood by reference to the accompanying drawing in which there is disclosed the terminal apparatus for a long submarine cable which terminates at a shore station and is there joined by a cable to a distant operating station.

Referring to the drawing, a cable C terminates at the shore station A which is joined to the operating station B by means of a cable comprising conductors 3, 4 of an operating loop and conductors 5, 6 of a control loop. At station A is located the sending condenser K, shaping network N and the amplifier S, while at the operating station B is located the transmitter T and the receiving mechanism R. The conductor 7 of cable C is associated either with sending condenser K or with receiving network N, or grounded by means of the contacts of polarized relay 8. A pair of polarized sending relays 9 and 10 have their upper or operating windings connected in series with each other and the operating loop conductors 3, 4. The lower windings of these relays are also connected in series with each other and a source of energy 11 which is for the purpose of biasing the relays. By the operation of these relays, the sending condenser K is connected to either the positive or negative terminal of battery 12 and it may be grounded through the armature of relay 10. The operating windings of relays 9 and 10

are associated with the operating loop by means of the lower contact springs of polarized relay 13. The input circuit of amplifier S is permanently connected to the network N as shown and the output circuit is connected through the lower contact springs of relay 14 with the operating loop 3, 4. The lower right hand contact springs of relay 14 control the operation of relay 15, the right hand contact springs of which are employed to connect the receiving network N to the cable conductor 7, while the left hand contact springs of this relay control the operation of relay 16 which is employed to short circuit amplifier S in the manner described in detail in the copending Curtis application, referred to above. The upper winding of relay 16 is associated with battery 2 for the purpose of biasing the relay.

20 A spring controlled receiving key 17 including the cam member 18 associated with battery 19, the positive terminal of which is grounded, and a similar sending key 20 provided with a cam member 21 connected to the positive terminal of grounded battery 22, are connected across the control loop conductors 5, 6. Indicating lamps 23 and 24 are associated with battery 25 by means of the upper contacts of relays 13 and 14 to indicate whether the sending or receiving apparatus is connected to the line.

At station B, a pair of spring controlled keys 27 and 28 corresponding to keys 17 and 20 and comprising respectively a cam member 29 connected to the negative terminal of grounded battery 30 and a cam member 31 connected to the positive terminal of grounded battery 32 are associated with control loop conductors 5, 6 for the purpose of controlling the operation of polarized relays 35 and 36 which correspond to relays 13 and 14 at station A. The upper contacts of these relays are adapted to control the connection of indicating lamps 37 and 38 to the battery 40. The lower contacts of relay 36 are adapted to connect and disconnect the receiver R from the operating loop 3, 4 and the lower contacts of relay 35 in a similar manner control the switching of transmitter T to the operating loop 3, 4. This transmitter which is of the standard tape controlled type is adapted to connect the battery 41 to the lower or operating winding of transmitting relay 42 or the lower or operating winding of transmitting relay 43 depending upon whether a dot or dash is to be transmitted. The intermediate windings of relays 42 and 43 are connected in series and to a battery 44 for the purpose of giving these relays the desired bias. The upper windings of relays 42 and 43 are connected in series and in cooperation with their contacts and the locking lever 45 provide undistorted impulses of the maximum length possible for the sending speed. The

contacts of these relays are adapted to connect the sending battery 46 through contacts of relay 35, operating loop 3, 4 contacts of relay 13 to the upper or operating windings of sending relays 9 and 10 and thereby control the operation of relays 9 and 10.

With the various relays operated in the direction shown, the system is arranged for sending. As the transmitter T is operated in the well known manner by means of a perforated tape, positive or negative impulses corresponding to dots or dashes are transmitted from battery 46 and cause the operation of relays 9 and 10. In the position shown for the armatures of relays 42 and 43, this operating circuit may be traced from the positive terminal of battery 46 through outer contact and armature of relay 43, lower right hand contacts of relay 35, conductor 3 of the operating loop, lower right hand contacts of relay 13, the operating windings of relays 10 and 9 in order, lower left hand contacts of relay 13, conductor 4 of the operating loop, lower left hand contacts of relay 35, armature and inner contact of relay 42 and back to the negative terminal of battery 46. The armatures of relays 9 and 10 are thus energized in such a manner that they correspond in position respectively with the armatures of transmitting relays 42 and 43. With relays 9 and 10 thus operated, the positive terminal of sending battery 12 is connected through the inner contact and armature of relay 10 to ground and the negative terminal of battery 12 is connected through the outer contact and armature of relay 9 to the sending condenser K and thence through contact springs 50 and 51 to conductor 7 of cable C. A negative impulse is thus, at this particular instant, being transmitted over cable C.

The receiving mechanism R is disconnected from the operating loop by the open lower contacts of relay 36. The input circuit of network N is short circuited by means of the right hand contacts of relay 15. With the armature of relay 16 in the position shown, a short circuit is placed across amplifier S in the manner previously referred to. So long as control members 17, 20, 27 and 28 remain unoperated, relays 42 and 43 will be operated in accordance with the perforations in the tape being fed through transmitter T and will cause the armatures of relays 9 and 10 to assume corresponding positions, thus connecting positive battery, negative battery or ground to the cable conductor.

When it is desired to change from the sending to the receiving position, either key 17 or 27 is operated dependent upon whether the system is being controlled at station A or station B. In the operation of these keys, a handle is turned to wind up a spring member which in turn slowly

rotates the cam member one complete revolution in a counter clockwise direction. Assuming that key 17 is operated, cam member 18 momentarily engages its left hand contact member, thus completing a circuit from the negative terminal of grounded battery 19 through cam member 18, left hand contact spring of key 17 and thence in parallel through the windings of relay 8, relay 13 and relay 35 to ground. Upon the energization of relay 8, contact spring 50 first engages contact spring 54, thereby connecting conductor 7 and one terminal of the sending condenser K simultaneously to local ground. Upon further movement of the armature, contact spring 51 breaks engagement with contact spring 50, thereby disconnecting the conductor 7 from sending condenser K and local ground. When the movement of the armature is completed, contact spring 51 is in engagement with spring 55, thereby connecting conductor 7 through the intermediate contacts of relay 15 to the sea ground 60. Upon the operation of relay 13, sending relays 9 and 10 are disconnected from operating loop 3, 4 by means of the lower contact springs of relay 13 and the upper left hand contact springs of this relay are closed, thereby completing a circuit from battery 25, through the left hand contacts and receiving lamp 24 to ground, causing this lamp to be lit. Sending lamp 23 also remains lit by current flowing from battery 25, through the left hand upper contact of relay 14 and lamp 23 to ground. The operation of relay 35 at station B, results in the transmitting mechanism being disconnected from the line by the opening of the lower contacts of relay 35, and receiving lamp 38 is lit by current flowing from battery 40 through the upper left hand contacts of this relay and lamp 38 to ground, lamp 37 remaining lit by current flowing from battery 40, through the upper left hand contact springs of relay 36 and lamp 37 to ground.

In the operation of key 17, cam 18 after wiping over the left hand contact, slowly continues to rotate and just before the end of the complete revolution, after a period of approximately ten seconds, it engages the right hand contact spring. When this contact spring is engaged, a circuit is completed from the negative terminal of grounded battery 19 through cam 18, right hand contact of key 17 and thence in a parallel path to ground through the windings of relays 14 and 36. Upon the energization of relay 36, its armature is moved in the reverse direction, thereby opening the upper left hand relay contacts and closing the lower contacts. The opening of the upper left hand contacts results in extinguishing sending lamp 37 and the closing of the lower contact springs of this relay connects the re-

ceiving mechanism R to the operating loop 3, 4. As relay 14 operates, the upper left hand contacts are opened, thus opening the battery supply circuit and extinguishing sending lamp 23; the lower left hand and intermediate contacts of relay 14 are closed connecting operating loop 3, 4 to the output circuit of amplifier S and the right hand movable contact spring engages its front contact thereby completing an energizing circuit for relay 15 from grounded battery 53 through the right hand front contact springs and the winding of the relay to ground and causing the relay armature to be moved in the reverse direction.

The opening of the intermediate contacts of relay 15 disconnects the sea ground 60 from the right hand contact springs of relay 8 to which in turn is connected the cable conductor 7, and as the movable spring of the intermediate contacts engages one of the right hand contact springs, cable conductor 7 is connected through the contacts of relays 8 and 15 to the upper input terminal of network N which at this instant is connected to the sea ground 60 by means of the right hand contacts of relay 15. Upon further movement of the armature, the right hand contacts of relay 15 are open thereby disconnecting the sea ground from both the cable and the upper terminal of the network. The left hand contacts of relay 15 are then closed completing an energizing circuit for relay 16 which may be traced from the negative terminal of grounded battery 53 through the right hand front contacts of relay 14, through the left hand contacts of relay 15 and the operating windings of relay 16 to ground. The armature of relay 16 moves to its alternate position, thus completing the final step of the operation by removing the short circuit previously placed across amplifier S.

The circuit as it now stands is completely arranged for receiving impulses transmitted from the distant station over cable C. These impulses are first transmitted to the input circuit of amplifier S and after being suitably amplified are transmitted over operating loop 3, 4 to the receiving mechanism R. The short circuit has been removed from amplifier S, rendering it operative and indicating lamps 24 and 38 are lit indicating that the system is in readiness to receive signals.

When it is desired to again place the apparatus in condition for transmitting messages, either key 20 or 28 is operated. Assuming that the former is operated, cam 21 first engages the left hand contact of key 20 thereby completing the circuit from the positive terminal of grounded battery 22 through cam 21, left hand contact of key 20 and then in parallel through the windings of relays 14 and 36 to ground, causing

the armatures of these relays to again assume the positions shown in the drawing. Upon the operation of relay 36, the lower contacts are again opened, thus disconnecting the receiving mechanism R from the operating loop 3, 4. Upon the closing of the upper left hand contacts of relay 36, the battery supply circuit for lamp 37 is again closed, causing this lamp to be lit while lamp 38 also remains lit. In a similar manner the operation of the upper contacts of relay 14 results in the lighting of lamp 23 at station A, lamp 24 remaining lit. The lower left hand and intermediate contacts of relay 14 are opened thereby disconnecting the output circuit of amplifier S from operating loop 3, 4. The right hand back contacts of relay 14 being closed, a circuit is completed from the positive terminal of battery 52 through the lower right hand back contacts of the relay and then in parallel through the winding of relay 15 and through the left hand contacts of relay 15 and the winding of relay 16 to ground. The operation of relay 16 connects a short circuit across amplifier S. As relay 15 is operated to the position shown, the sea ground 60 is connected to the upper terminal of network N through the right hand contacts of relay 15 and to conductor 7 through the intermediate contacts of relay 15 and the right hand contacts of relay 8. The left hand contacts of relay 15 which control the operation of relay 16 are again opened.

Cam 21 continues to rotate slowly for a period of approximately ten seconds until it reaches the point where it engages the right hand contact spring of key 20, thus completing energizing circuits for relays 8, 13 and 35. As relay 8 is operated, contact spring 51 moves out of engagement with spring 55, thus disconnecting cable conductor 7 from the intermediate contacts of relay 15 which in turn are connected to the sea earth. Spring 51 next engages contact 50 thereby connecting cable conductor 7 to sending condenser K which remains grounded until the armature of relay 8 has moved a sufficient distance to separate springs 50 and 54 and thereby remove the ground connection. As relay 13 is operated, the lower contacts are engaged thereby connecting the operating windings of relays 9 and 10 with the operating loop 3, 4. The upper left hand contacts of relay 13 are opened and lamp 24 is accordingly extinguished. Upon the operation of relay 35 the lower contacts of this relay associate the sending mechanism T with its transmitting relays 42 and 43 and sending battery 46 with the operating loop 3, 4. The upper contacts of this relay are moved in a position to extinguish receiving lamp 38, leaving lamp 37 lit.

65 The system is now once more in condition

for transmitting messages. Transmitter T and its associated apparatus is connected over the operating loop 3, 4 with sending relays 9 and 10 which, upon operation, send positive, negative or zero impulses through the sending condenser K over cable conductor 7 to the distant station. The input circuit of network N is grounded by the contacts of relay 15 and amplifier S is short circuited by relay 16. Lamps 23 and 37 are 75 lighted and lamps 24 and 38 are unlighted, indicating that the apparatus at both stations is in position for transmitting messages.

While this invention has been described as embodied in a submarine cable system, 80 certain aspects of the invention are of broader application. This has been borne in mind in drafting the claims.

What is claimed is:

1. In a signaling system, a transmitting 85 conductor having a pair of stations located at one end thereof, transmitting and receiving mechanisms at one of said stations, and means operable at either of said stations to associate either the transmitting mechanism 90 or the receiving mechanism with the conductor.

2. In a signaling system, a transmitting conductor having a pair of stations located at one end thereof, transmitting and receiving mechanisms at one of said stations, means operable at either of said stations to associate either the transmitting or the receiving mechanism with the conductor and means for grounding the conductor when switching 100 from the sending to receiving positions.

3. In a signaling system, a transmitting conductor having a pair of stations located at one end thereof, transmitting and receiving mechanisms at one of said stations, 105 switching means operable at either of said stations to connect either the transmitting or the receiving mechanism with the conductor, means for grounding the conductor when switching from the sending to the receiving 110 positions, and means for short circuiting the amplifier during a portion of the switching interval.

4. In a signaling system, a cable having a pair of stations located at one end thereof, 115 transmitting and receiving mechanisms at one of said stations, an amplifier and sending condenser at the other of said stations, means operable at either station for disconnecting the transmitter with its associated 120 sending condenser from the cable and connecting thereto the receiving mechanism and its associated amplifier.

5. In a signaling system, a cable having a pair of stations located at one end thereof, 125 transmitting and receiving mechanisms at one of said stations, an amplifier and sending condenser at the other of said stations, and means operable at either of said stations for sequentially disconnecting the transmit- 130

- ting mechanism from the cable, short circuiting the sending condenser, grounding the cable, and connecting the receiver and its associated amplifier to the cable.
6. In a signaling system, a cable having a pair of stations located at one end thereof, transmitting and receiving mechanisms at one of said stations, an amplifier and sending condenser at the other of said stations, means operable at either of said stations for sequentially disconnecting the transmitting mechanism from the cable, short circuiting the sending condenser, grounding the cable and connecting the receiving mechanism and its associated amplifier to the cable, and means for short circuiting the amplifier during the switching operations.
7. In a signaling system, a cable having a pair of stations located at one end thereof, a transmitting and a receiving mechanism located at one of said stations, an amplifier and a sending condenser located at the other of said stations, means operable at either of said stations for automatically connecting the transmitter with an associated sending condenser to the cable or for connecting thereto the receiver with its associated amplifier, and means for indicating which apparatus is connected to the cable.
8. In a signaling system, a cable having a pair of stations located at one end thereof, a transmitting and a receiving mechanism located at one of said stations, an amplifier and a sending condenser located at the other of said stations, means operable at either of said stations for automatically connecting the transmitter with its associated sending condenser to the cable or for connecting thereto the receiver with its associated amplifier, and indicating means at each of said stations to indicate the position of the switching means.
9. In a signaling system, a loaded cable, having a pair of stations located at one end thereof, a receiving mechanism, a transmitting mechanism, and common means operable at either of said stations for disconnecting one of said mechanisms from the cable and connecting the other thereto, provision being made for grounding the cable between said operations for a period of time sufficient to drain off the major portion of the potential energy resulting from the previous transmission of signals.
10. In a signaling system comprising a cable and a pair of stations associated with one end of the cable, transmitting and receiving mechanisms at said stations, a portion of both the transmitting and receiving mechanisms being located at one of said stations and another portion of both said transmitting and receiving mechanisms being located at the other of said stations, and means at each station for associating either the transmitting or the receiving mechanisms with the cable.
11. In a signaling system, a cable having a pair of stations located at one end thereof, transmitting and receiving mechanisms located at one of said stations, and cam operated circuit-closing devices operable at either of said stations for disconnecting the transmitting mechanism from the cable, grounding the cable for a given interval of time and then connecting the receiving mechanism thereto.
12. In a signaling system comprising a loaded submarine cable having a pair of separate stations at one end thereof joined together by a second cable comprising an operating loop and a control loop, transmitting and receiving mechanisms located at one of said stations, an amplifier and sending condenser located at the other of said stations and means operable at either of said stations cooperating with the control loop for simultaneously operating switching mechanisms at both stations whereby either the transmitting mechanism with its associated sending condenser or the receiving mechanism with its associated amplifier is connected to the cable over the operating loop.
13. In a signaling system, a transmission conductor, transmitting and receiving mechanisms located at one terminal of said conductor and cam operated circuit closing devices operable at said station for disconnecting the transmitting mechanism from the conductor, grounding the conductor for a given interval of time and then connecting the receiving mechanism thereto.
14. In a signaling system, a transmission conductor, transmitting mechanism including a sending condenser and receiving mechanism including an amplifier, all located at one terminal of said conductor, and means operable at said terminal for sequentially disconnecting the transmitting mechanism from the conductor, short circuiting the sending condenser, grounding the conductor and connecting the receiver and its associated amplifier to the conductor.
15. In a signaling system, a transmission conductor, transmitting mechanism including a sending condenser and receiving mechanism including an amplifier, all located at one terminal of said conductor, means operable at said terminal for sequentially disconnecting the transmitting mechanism from the conductor, short circuiting the sending condenser, grounding the conductor and connecting the receiving mechanism and its associated amplifier to the conductor, and means for short circuiting the amplifier during the switching operations.
16. In a signaling system, a transmission conductor, transmitting mechanism includ-

ing a sending condenser and receiving mechanism including an amplifier, all located at one terminal of said conductor, means operable at said terminal for automatically connecting the transmitting mechanism with the associated sending condenser to the conductor or for connecting thereto the receiv-

ing mechanism with its associated amplifier, and means for indicating which apparatus is connected to said conductor. 10

In witness whereof, I hereunto subscribe my name this 2d day of October A. D. 1924.

GEORGE A. LOCKE.
